(57) **CLAIM**

The ornamental design for a cuff bracelet, as shown and described.

DESCRIPTION

FIG. 1 illustrates a perspective view of a cuff bracelet in accordance with an embodiment of the present invention.

FIG. 2 illustrates a top view of the cuff bracelet in accordance with an embodiment of the present invention.

FIG. 3 illustrates a front elevation view of the cuff bracelet in accordance with an embodiment of the present invention.

FIG. 4 illustrates a rear elevation view of the cuff bracelet in accordance with an embodiment of the present invention.

FIG. 5 illustrates a left side elevation view of the cuff bracelet in accordance with an embodiment of the present invention; and,

FIG. 6 illustrates a right side elevation view of the cuff bracelet in accordance with an embodiment of the present invention.

The cuff bracelet of the present invention includes a stylized surface contour that resembles a scrunched paper surface. FIGS. 1 through 6 include surface shadings, showing the character of the surface represented.
